UNITED STATES PATENT OFFICE.

ARTHUR G. TRIMBLE, OF PITTSBURGH, PENNSYLVANIA.

DESIGN FOR A CHRISTIAN-SERVICE FLAG.

54,972.

Specification for Design.

Patented Apr. 20, 1920.

Application filed February 28, 1919. Serial No. 279,896. Term of patent 14 years.

To all whom it may concern:

Be it known that I, ARTHUR G. TRIMBLE, a citizen of the United States, residing at Pittsburgh, in the county of Allegheny and State of Pennsylvania, have invented a new, original, and ornamental Design for a Christian-Service Flag, of which the following is a specification, reference being had to the accompanying drawing, forming part thereof.

The figure is a plan view of a Christian-service flag, showing my new design, and by reference thereto it consists of a cruciformed shaped figure or cross with the background below shorter arm of the cross and at each side of the longer arm blue, and the background above the shorter arm of the cross and at each side of the longer arm red.

I claim:

The ornamental design for a Christian service flag, as shown.

In testimony whereof I affix my signature.

ARTHUR G. TRIMBLE.
